(57) **CLAIM**

I claim, the ornamental design for the dual-compartment sandwich bag, as shown and described.

DESCRIPTION

FIG. 1 is a front elevational view of the dual-compartment sandwich bag showing my new design;

FIG. 2 is a left-side elevational view of the dual-compartment sandwich bag thereof;

FIG. 3 is a right side elevational view of the dual-compartment sandwich bag thereof; and,

FIG. 4 is a top plan view of the dual-compartment sandwich bag thereof.

1 Claim, 1 Drawing Sheet

FIG. 1

FIG. 2

FIG. 3
